VACUUM CLEANER

Albert A. Arnhym, San Diego, Calif., assignor to
 The Singer Manufacturing Company, Elizabeth,
 N. J., a corporation of New Jersey

Application March 18, 1942, Serial No. 435,231

3 Claims. (Cl. 15—8)

This invention relates to vacuum cleaners and it has as its primary object to provide improved means for maintaining the nozzle of a vacuum cleaner in a predetermined position relative to the surface of a floor-covering regardless of the character, texture or thickness of such covering.

Stated more specifically this invention has as an object to provide, in a vacuum cleaner, an automatically adjustable nozzle which will adapt itself to hard, soft, thick or thin floor-covering without any attention of the user.

It is well known that, in the absence of counteracting means, when operating a vacuum cleaner on soft, long-pile carpet the weight of the cleaner causes the wheels to sink into the carpet with the result that the entire cleaner is lowered toward the floor and the suction nozzle is brought into contact with the upper surface of the floor-covering with such pressure that efficient cleaning is not possible. To counteract this condition, it has long been the practice to provide vacuum cleaners with manually adjustable means whereby the operator may, at will, either raise or lower the nozzle to adapt the cleaner for the specific floor-covering to be cleaned. When cleaning a hard, smooth surface, such for example as a bare floor or linoleum, into which the wheels cannot sink under the weight of the cleaner, it has been the practice to lower the nozzle into close proximity to the floor or floor-covering. When operating on long pile carpet the nozzle is raised to compensate for normal lowering of the nozzle due to sinking of the wheels into the carpet pile.

This continuous adjustment and readjustment every time a different operating condition is encountered, which frequently happens, as when passing from one room to the other or even in a single room where both bare floors and carpet are to be cleaned, has been a constant source of annoyance to users; with the result that much attempted cleaning has been done with the vacuum cleaner out of adjustment for the particular job at hand.

More or less recently attempts have been made to provide automatic nozzle-height adjustment for vacuum cleaners. Certain ones of the devices heretofore provided for this purpose have been complicated in construction and therefore costly to manufacture and have involved the tipping of the entire vacuum cleaner. Others have employed relatively small or narrow rear wheels which are designed to sink into the carpet to a greater depth than do the front wheels, thereby tipping the cleaner and elevating the nozzle.

One disadvantage of this latter type of automatic adjustment is that, in many types of carpet, the furrows made by the rear wheels remain visible after the cleaning is completed. Obviously this is objectionable as it mars the appearance of the carpet.

This invention has as further objects to provide a vacuum cleaner having automatic nozzle height adjustment which is simple in construction; which does not involve tipping of the cleaner; and which permits the use of wheels of such proportions that they will adequately support the cleaner on any type of floor-covering without objectionably marking the same.

15 These and other objects have been attained by mounting a vacuum cleaner on wheels of uniform size and providing in the forward end of the vacuum cleaner casing a brush-carrying suction nozzle which is relatively light in weight and which is permitted to move vertically, or "float," in the casing so that the rotary dust brush carried by the nozzle will bear lightly on the floor-covering and the mouth of the nozzle will be maintained a slight distance above the surface level of the floor-covering. A flexible tubular sleeve is provided to connect the floating suction nozzle with the suction chamber of the cleaner.

With the above and other objects in view, as will hereinafter appear, the invention comprises the devices, combinations and arrangements of parts hereinlater set forth and illustrated in the accompanying drawing of a preferred embodiment of the invention, from which the several features of the invention and the advantages attained thereby will be readily understood by those skilled in the art.

In the drawing,

Fig. 1 is a longitudinal sectional view of a vacuum cleaner embodying the present invention, parts of the vacuum cleaner being broken away.

Fig. 2 is a transverse sectional view taken substantially on the line 2—2 of Fig. 1.

Fig. 3 is a plan view, on a reduced scale, of the vacuum cleaner shown in Figs. 1 and 2.

Referring more specifically to the drawing, the invention is disclosed as embodied in a vacuum cleaner comprising a base 1, mounted, by fixed bearings 2^a and 3^a, on a pair of front wheels 2, 2 and a pair of rear wheels 3, 3 all of substantially the same diameter and the same width. The base 1 is formed with a fan- or suction-chamber 4 in which is mounted a rotary suction fan 5 secured upon the shaft of an electric motor 6, supported upon the base 1. The base is provided

with an intake port 1, which leads to the eye 8 of the fan chamber, and a discharge port 9 to which the usual dust bag is connected. A handle 10, for operating the cleaner, is connected to the base 1 and motor 6, and secured thereto in any suitable or preferred manner. Overlying the base 1 and motor 6, and secured thereto in any suitable or preferred manner, is a hood or casing 11 having, at one end, a transversely arranged and horizontally disposed nozzle-hood portion 12, of substantially inverted U-shape in cross-section. This portion comprises a top wall 12^a and end walls 12^b and 12^c and has the appearance of the conventional intake nozzle. Mounted for vertical movement in the portion 12 is a suction nozzle 13, also of substantially inverted U-shape, having at its lower side an open mouth 14. The nozzle 13 comprises a top wall 13^a and end walls 13^b and 13^c located within and adjacent the walls 12^a, 12^b and 12^c, respectively, of the casing portion 12. Supported within the end walls of the suction nozzle 13 is a shaft 15 on which is journaled a rotary dust brush 16 of conventional form affording, at its mid portion, a belt pulley 17. A belt 18, driven from a spindle 19 carried by and projecting downwardly from the rotary fan 5, engages the pulley 17 and thereby rotates the brush 16 from the electric motor 6.

The nozzle 13 is guided and limited in its movements in the portion 12 of the casing 11 by having the projecting ends 15^a and 15^b of the shaft 15 fitted in and engaging the walls of slots 20 and 21 formed in the end walls 12^b and 12^c, respectively, and by pins 22 and 23 carried by the nozzle 13 slidably fitted within slots 24 and 25, also formed in said end walls. The end walls 12^c is removably secured to the portion 12 so as to permit ready assembly and removal of the parts.

Projecting rearwardly from the nozzle 13, substantially midway between its ends, is a tubular extension 26 which serves as a discharge port for the nozzle. This extension is connected with the intake port 1 of the casing 1 by a flexible tubular sleeve 27, of any suitable material which, if desired, may have wire rings 28 mounted therein to prevent collapsing of the sleeve. By reason of this construction, the suction nozzle is free to float vertically in the casing 11 while being maintained in dust tight connection with the suction chamber. The brush-driving belt 18 extends through the extension 26, the sleeve 27 and intake port of the casing 1, as shown in Fig. 1.

In operation, the suction nozzle is permitted to move vertically in the casing an amount determined by the slots 20, 24 and 21, 25 and normally will gravitate toward the lower ends of those slots. When the cleaner is placed upon a floor or floor-covering to be cleaned the ends of the bristles of the brush will engage the upper face of the surface to be cleaned and the mouth 14, being spaced thereabove, will be maintained a predetermined distance above such surface regardless of the amount (within normal limitations) which the wheels of the vacuum cleaner may sink into the floor-covering due to the weight of the cleaner. In Fig. 1 the suction nozzle 13 is shown, in full lines, in its uppermost position as when cleaning a long pile carpet, and, in dotted lines, in its lowermost position as when cleaning a bare floor or a hard surface floor covering, such as linoleum. In cleaning floor-coverings between these two extremes the nozzle will assume a position somewhere between the two

positions illustrated. When cleaning carpet, the carpet may be sucked partially up into the nozzle mouth as indicated in dot-dash lines. This facilitates cleaning as is well understood.

5 Having thus set forth the nature of the invention what I claim herein is:

1. A vacuum cleaner comprising a base affording a fan-chamber, an intake port connected with the eye of the fan-chamber and a discharge port connected with the periphery of the fan-chamber, a motor-driven fan in said fan-chamber, a casing overlying said base and provided, at its front end, with a portion having top and end walls, each of said end walls being provided with a pair of vertically arranged slots, a suction nozzle mounted in said portion for vertical movement, said nozzle having top and end walls, an open mouth at its lower side and a rearwardly extending discharge port, a pin projecting from each end wall of said nozzle and entering one of the slots in the adjacent end wall of said casing, a horizontally arranged shaft mounted in the end walls of said nozzle and projecting outwardly therefrom and entering the other slot in the adjacent end walls of the casing, a rotary brush journaled on said shaft, a flexible tubular connection between the discharge port of said nozzle and the intake port of said fan-chamber, and means for rotating said brush.

30 2. In a vacuum cleaner, the combination with a base affording a suction chamber and a forwardly extending tubular portion, and a casing overlying said suction chamber and having a transversely disposed nozzle-hood of inverted U-shape in cross section and formed with top and end walls, said end walls each being provided with a vertically arranged slot; of a suction nozzle, having a rearwardly extending tubular portion, mounted for free vertical sliding movement 35 in said nozzle-hood; pins projecting from the ends of said nozzle and entering said slots to guide and limit the movement of said nozzle; and a flexible tubular connection between said forwardly and said rearwardly extending portions 40 to connect said nozzle with said suction chamber.

45 3. In a vacuum chamber, the combination with a base affording a suction chamber and a forwardly extending tubular portion, and a casing overlying said suction chamber and having a transversely disposed nozzle-hood of inverted U-shape in cross section and formed with top and end walls, said end walls each being provided with a vertically arranged slot; of a suction nozzle 50 of inverted substantially U-shape in cross section mounted for free vertical sliding movement in said nozzle-hood and having a rearwardly extending tubular portion; pins projecting from the ends of said nozzle and entering 55 said slots to guide and limit the movement of said nozzle; a brush rotatably journaled in said nozzle, said nozzle and brush being free to gravitate in said nozzle-hood until the brush contacts an underlying floor surface; a flexible tubular connection between said forwardly and rearwardly 60 extending portions to connect said nozzle with said suction chamber; and means extending through said forwardly and said rearwardly extending portions and said flexible tubular connection to rotate said brush.

ALBERT A. ARNHYM.
